[57] **ABSTRACT**

A pick-up lift assembly for raising the pick-up for a hay baler to a transport position or lowering the pick-up to a working position and for holding the pick-up in the desired position. The lift assembly includes a lift arm with a series of notches pivotally attached to the pick-up and retained on the side of the bale chamber by guides. The lift arm is raised by a rope which is pulled by a drive shaft that forms a capstan drive. A lift latch engages the notches in the lift arm to hold the pick-up in the desired position. An overcenter coil spring is connected to bias the lift latch into or out of engagement with the notches. Upon raising the pick-up with the rope from the transport position, a first cam on the lift arm contacts a first cam surface on the upper portion of the lift latch and cams the latch until the coil spring is moved past center and biases the lift latch away from the notches. The pick-up and lift arm can then be lowered until a second cam contacts a second cam surface on the lift latch and cams the latch until the coil spring is moved past center and biases the lift latch toward the notches. The lift latch then engages one of the notches preventing further lowering of the lift arm and holding the pick-up in a working position. The second cam is adjustable relative to the notches to adjust the working position. The lift arm is attached to the pick-up by a linkage assembly which includes a lost motion connection and a spring which assist the pick-up to float up over obstructions.

BALER PICK-UP LIFT ASSEMBLY

This invention relates to an improved hay baler and more specifically to a pick-up lift assembly for raising and lowering a pick-up for a baler.

Hay balers, which are pulled through a hay field by tractor, normally have a pick-up assembly for picking hay up off the ground and feeding the hay into a feed housing. From the feed housing the hay is conveyed into the bale chamber, by packer fingers, where it is compressed and tied to form a bale.

The pick-up normally has rows of teeth which protrude through the space between a series of arcuate stripper assemblies to pick hay up off the ground and convey it into the feed housing. The teeth are mounted on a drum which is rotated by the pick-up drive. The pick-up is pivotally attached to the frame of the baler so that the teeth can contact the ground for operation or be raised above the ground for transport.

The pick-up preferably includes an adjustable gage wheel which lets the pick-up float over rough spots in the field. However, the gage wheel does not raise the pick-up high enough above the ground for crossing irrigation ditches or for road transport. With most hay balers it is necessary for the operator to get off the tractor, physically raise the pick-up, fasten the pick-up in the raised position and then return to the tractor. For transporting the baler from one field to another it is not too tiring for the operator to get off the tractor to raise the pick-up. However, if there are a number of obstructions in the field, such as irrigation ditches which must be crossed, in addition to losing considerable working time the operator will eventually tire of climbing off and on the tractor.

The hay baler of this invention includes a frame supported on wheels, a bale chamber mounted on the frame and a feed housing mounted on the frame. A packer assembly is mounted on the frame to feed hay from the feed housing to the bale chamber. A pick-up is pivotally attached to the baler frame to pick hay up off the ground and feed it into the feed housing. A pick-up lift assembly is provided to assist the operator in moving the pick-up between a transport position and a working position without leaving the tractor. The pick-up lift assembly includes a pick-up lift arm with a series of notches and a lift latch, capable of engaging each of the notches in the lift arm, pivotally attached to the baler. The lift latch is biased into or out of engagement with the notches in the lift arm by an overcenter spring. The lift latch and overcenter spring are tripped into or out of engagement with the notches by a pair of cams which engage cam surfaces on the lift latch. The lift arm includes a lost motion mechanism which is capable of permitting the pick-up to float up and down as the baler moves through a field. The working position of the baler pick-up is adjustable by adjusting the position of one of the cams relative to the notches on the lift arm. The pick-up is raised and lowered by a rope which is trained around a shaft that forms a capstan type drive. One end of the rope is attached to the pick-up and the other end is pulled by the operator.

A preferred embodiment of the invention will now be described with reference to the drawing in which:

FIG. 1 is a fragmentary perspective view of a hay baler employing the novel pick-up lift assembly of this invention;

FIG. 2 is an enlarged fragmentary side elevational view of the pick-up lift assembly shown in FIG. 1;

FIG. 3 is an enlarged side elevation of the latch portion of the pick-up lift assembly shown in FIGS. 1 and 5 2;

FIG. 4 is a front elevation of the latch portion of the pick-up lift assembly shown in FIG. 3;

FIG. 5 is a sectional view of the latch portion of the pick-up lift assembly taken on the line 5-5 of FIG. 3; and

FIG. 6 is a sectional view of the latch portion of the pick-up lift assembly taken on the line 6-6 of FIG. 3.

The pick-up lift assembly of this invention is for use on a conventional hay baler. The baler, a portion of which is shown in the drawing includes a frame 10 supported by wheels 12. A pick-up 14 is pivotally attached to the frame 10 by a pair of support assemblies 16 which are rigidly attached to the frame. The support assemblies 16 each include a U-shaped bracket 18 which support a circular tube 20 extending from each side of the rear portion of the pick-up 14. The circular tube 20 is held in the U-shaped brackets 18 for pivotal movement by removable pins 22.

The pick-up 14 includes a pair of end plates 24 and 26, a plurality of arcuate stripper sections 28 and pick-up fingers 30. The pick-up fingers 30 are mounted on a drum which is rotated so that the pick-up fingers lift hay off the ground and convey the hay up and to the rear on the arcuate stripper sections 28.

A gage wheel 32 is rotatably attached to a support arm 34 by an axle 36. The support arm 34 is adjustably connected to a bracket 38 on the end plate 24 by a bolt 40. The gage wheel 32 limits movement of the pick-up 14 about the axis of the circular tube 20 to control contact of the pick-up fingers 30 with the ground. The gage wheel 32 also assists the pick-up 14 to move over uneven fields.

The hay from the pick-up 14 is moved from the arcuate stripper sections 28 and into the feed housing 42. The feed housing 42 is defined by a bottom plate 44, a rear wall 46 and one side wall 48, all of which are rigidly attached to the frame 10.

The hay received in the feed housing 42 is conveyed away from the side wall 48 and into the open side of a bale chamber 50 by a conventional packer fork assembly 52. The packer fork assembly 52, which is partially hidden by the packer cover assembly 54, includes two sets of packer fingers 56. The packer fingers 56 are driven by a packer fork assembly drive so as to convey hay from the feed housing 42 to the bale chamber. A packer relief spring assembly 58 is operatively connected to the packer fingers 56 of the packer fork 60 adjacent to the bale chamber 50 by a pin 62. The packer relief spring assembly 58 limits the force which the packer fingers 56 adjacent to the bale chamber 50 apply to the hay conveyed into the open side of the bale chamber. The packer fork assembly drive and the pick-up 14 are driven by a drive shaft 64 shown in FIG. 2. The drive shaft 64, which is under the packer cover assembly 54, is rotated in a counterclockwise direction as shown in FIG. 2.

A conventional plunger in the bale chamber 50 compresses the hay fed into the bale chamber by the packer fingers 56 into a bale. Wire or twine is tied around the compressed bale by a conventional knoter before the

bales are forced out of the bale chamber 50 by the plunger. The plunger is connected to a crank shaft by a connecting rod. The crank shaft, which is under the plunger crank cover 66, is driven to reciprocate the plunger back and forth in the bale chamber 50.

A pick up lift assembly 68 which is best shown in FIG. 2 is provided for raising and lowering the pick-up 14. The pick-up lift assembly 68 includes a base plate 70 rigidly attached to the side of the bale chamber 50 by bolts 72. A lift arm 74 with one end attached to the end plate 26 of the pick-up 14 is spaced to one side of the base plate 70 and the bale chamber 50 where it is guided for vertical movement. The lower guide 76 for the lift arm 74 is bolted to the side of the bale chamber 50 below the base plate 70 by bolts 78. The lower guide 76 has a vertical opening with the same size and shape as a cross section of the lift arm 74. The upper rear guide 80 is a flat member welded to the base plate 70 with a notch 82 as shown in FIG. 5 for receiving the rear edge of the lift arm 74. The upper front guide is formed by a flat member 84, with a notch 86 in one corner, welded to the base plate 70 and a metal strap 88 welded to the edge of the flat member 84 so as to overlap the notch 86 and to extend up above the flat member 84. The metal strap 88 is adjacent to the notches 90 in the forward edge of the lift arm 74 to prevent the notches 90 from catching on the flat member 84.

The pick-up 14 is raised by a rope 92 with one end attached to the lift arm 74 by a clamp 94 and a bolt 96. The rope 92 extends up from the clamp 94, between the lift arm 74 and the base plate 70, around a pulley 98 pivotally attached to the upper portion of the base plate 70 by a shaft 100, through an aperture 102 in the packer cover assembly 54, around the drive shaft 64 at least one complete turn, through the aperture 103 and to a point adjacent to the operator's station. When there is little or no tension on the rope 92, the drive shaft 64 turns free. When the operator pulls on the end of the rope 92 adjacent to the operator's station, the drive shaft 64 becomes a capstan and pulls on the rope 92 thereby raising the lift arm 74 vertically in the guides and raising the pick-up 14.

If the operator reduces the tension on the rope 92, friction between the rope 92 and the surface of the drive shaft is reduced and the lift arm 74 is free to move down. A lug 93 is welded to the base plate 70 to keep the rope 92 on the pulley 98 when the rope 92 is loose.

A lift latch 104 is provided to hold the lift arm 74 in the desired position. The lift latch 104 is pivotally supported on a pin 106 extending horizontally from a plate 108 welded to the base plate 70. The lift latch 104 is retained on the pin 106 by a cotter pin 110. The upper surface 111 of the lift latch 104 engages one of the notches 90 in the forward edge of the lift arm 74 when the lift latch 104 is rotated counterclockwise about the pin 106 as shown in FIGS. 2 and 3 thereby preventing further downward movement of the lift arm 74.

A coil spring 112 best shown in FIGS. 3 and 4 has one end pivotally received in an aperture 114 in the lower portion of the lift latch 104. The other end of the coil spring 112 is pivotally received in an aperture 118 in the plate 108. The axes of both apertures 114 and 118 are parallel to the axis of the pin 106. The aperture 118 is spaced farther from the pin 106 than the aper-

ture 114. Since the coil spring 112 tends to uncoil, the lift latch 104 is biased in a counterclockwise direction about the pin 106 as shown in FIG. 3. When the aperture 114 crosses an imaginary line between the aperture 118 and the axis of the pin 106, during clockwise rotation of the lift latch 104 about the axis of the pin 106 as shown in FIG. 3, the coil spring 112 tends to bias the lift latch 104 in a clockwise direction. The portion 5 of the lift latch 104 below the axis of the pin 106 is a skirt 120 as shown in FIG. 4 which does not contact the lift arm 74.

When the operator pulls on the rope 92, the lift arm 74 is moved vertically upward in the guides with the help of the drive shaft 64. The surface 122 of the lift latch 104 slides along the ramp portion 124 of one of the notches 90, thereby rotating the lift latch 104 against the coil spring and out of the notch 90. As the lift arm 74 continues to move vertically up the lift latch 15 will be biased into each notch 90 by the coil spring 112. Any time the tension in the rope 92 is released, the upper surface 111 of the lift latch 104 will engage the closest higher notch 90 as the lift arm 74 moves down and thereby prevents further downward movement of the lift arm 74. The lowest notch 90 on the lift arm 74 is 20 for transport only. The notches 90 adjacent to the upper end of the lift arm 74 are for operation of the baler.

To move the lift arm 74 from the transport position 30 to the working position, the lift arm 74 is raised so that the first cam 126 on the forward edge of the lift arm 74 contacts a first cam surface 128 on the upper portion of the lift latch 104. Continued upward movement of the lift arm 74 results in the lift latch 104 being rotated clockwise by the first cam 126 until the coil spring 112 moves over center and biases the upper surface 111 35 and the surface 122 of the lift latch 104 away from the notches 90. If desired, a stop can be provided which will stop further upward movement of the lift arm 74. 40 The stop could be a projection on the lift arm 74 which would contact the upper rear guide 80. After the coil spring 112 has moved to a position where the lift latch 104 is biased in a clockwise direction about the pin 106 as viewed in FIG. 3, a release of tension in the rope 92 45 will allow the lift arm 74 to move downward in the guides. As the lift arm 74 moves down, the lower portion of a second cam 130, attached to the side of the lift arm 74 by bolts 132 and 134, will contact a second cam 50 surface 136 on the skirt 120 of the lift latch 104 that is adjacent to the side of the lift arm 74. As the lift arm 74 continues to move downward, the lift latch 104 is rotated counterclockwise, about the axis of the pin 106 55 as viewed in FIG. 3, by the second cam 130 until the coil spring 112 is moved to a position in which the upper surface 111 and the surface 122 of the lift latch 104 are biased toward the notches 90. The lift latch 104 will engage the first notch 90 which it contacts thereby preventing further downward movement of the lift arm 74.

Several notches 90 are provided in the upper portion 60 of the lift arm 74 so that the working position of the pick-up 14 can be varied. The adjustment in the working position of the pick-up 14 is made by changing the position of the lower end of the second cam 130 relative to the notches 90. This adjustment is made by removing the bolts 132 and 134, moving the angle iron

which forms the second cam 130 up or down relative to the notches 90 to the desired position and then reinserting the bolts 132 and 134 in the appropriate holes 138. A sleeve 135 is placed on the bolt 132 to form a handle for raising the lift arm 74 when the drive shaft 64 is not running.

The lower end of the lift arm 74 is pivotally attached to the end plate 26 of the pick-up 14 by a rod 140. The lower end of the rod 140 is inserted through an aperture in a wear plate 142 welded to the end plate 26. The rod 140 can be retained in the wear plate 142 by being bent as illustrated in FIG. 4, or a cotter pin could be inserted through the rod 140. The upper end of the rod 140 is attached to the lift arm 74 by being inserted through an aperture 144 in a bracket 146 welded to the side of the lift arm 74. A stop member 148 that is rigidly attached to the upper end of the rod 140 contacts the upper surface of the bracket 146 thereby limiting downward movement of the pick-up 14 relative to the lift arm 74. The rod 140 is free to move up through the aperture 144 to allow the pick-up 14 to float up over obstructions.

A compression spring 150 is retained on the upper portion of the rod 140 between the bracket 146 and a washer 152 held on the top of the rod 140 by a pin 154. The pin 154 is held in an aperture through the rod 140 by a standard retainer spring 156. The compression spring 150 is held in the proper position by a retainer skirt 158 on the washer 152 and the stop member 148 which forms an internal guide for the compression spring 150. The compression spring tends to lift the pick-up 14 thereby assisting the pick-up to float over obstructions.

In operation, the pick-up 14 is moved from the transport position with the lift latch 104 in engagement with the lower notch 90 in the lift arm 74 by placing tension in the rope 92. The tension in the rope 92 causes the drive shaft 64 to raise the lift arm 74 in the guides until the lift latch 104 is cammed by a first cam 126 to a position in which the coil spring 112 holds the lift latch 104 out of contact with the lift arm 74 and the notches 90. Tension in the rope is then released. This allows the pick-up 14 and the lift arm 74 to move down until the lift latch 104 is cammed by a second cam 130 to a position in which the coil spring 112 biases the lift latch 104 toward the lift arm 74. Continued downward movement of the lift arm 74 causes the lift latch 104 to engage the closest notch 90 and thereby prevent further downward movement of the pick-up 14. The notch 90 which the lift latch 104 engages during lowering of the pick-up 14 from the transport position depends upon the position of the lower end of the second cam 130 relative to the lift arm 74. To raise the pick-up 14 to the transport position, tension is maintained on the rope 92 to raise the pick-up 14 until the lift latch 104 engages the lower notch 90 in the lift arm 74.

We claim:

1. An improved hay baler having a frame, wheels to support the frame, a bale chamber mounted on the frame, a feed housing mounted on the frame, a packer assembly capable of feeding hay from the feed housing to the bale chamber mounted on the frame, a pick-up capable of conveying hay from the ground to the feed housing pivotally attached to the frame and drive means to drive the pick-up characterized by a pick-up lift assembly, capable of raising the pick-up to a transport position or lowering the pick-up to a working position and holding the pick-up in the desired position, including a pick-up lift arm, a series of notches in the lift arm, a lift latch capable of engaging each of the notches in the lift arm to prevent movement of the lift arm relative to the lift latch in one direction, pin means pivotally attaching the lift latch to the baler, an over-center spring capable of biasing the lift latch into and out of engagement with the notches in the lift arm, a first cam surface on the lift latch, a second cam surface on the lift latch, a first cam on the lift arm capable of engaging the first cam surface on the lift latch when the pick-up is raised above the transport position by the pick-up lift and pivoting the lift latch until the over-center spring moves past center and holds the lift latch out of contact with the notches in the lift arm thereby allowing the pick-up to be lowered by the force of gravity and a second cam on the lift arm capable of engaging the second cam surface on the lift latch when the pick-up is lowered and pivoting the lift latch until the overcenter spring moves past center and biases the lift latch into one of the notches in the lift arm thereby preventing further downward movement of the pick-up.
2. The improved hay baler of claim 1 characterized by said lift arm including a lost motion mechanism which is capable of permitting the pick-up to float up and down as the baler moves through a field.
3. The improved hay baler of claim 1 characterized by the second cam including adjusting means capable of providing adjustment of the second cam relative to at least some of the notches on the lift arm to adjust the working position of the pick-up.
4. The improved hay baler of claim 1 characterized by the lift latch being attached to the bale chamber by said pin means, the lift arm being attached to the pick-up and the lift assembly further including guide members on the bale chamber to hold the lift arm in alignment relative to the lift latch.
5. The improved hay baler of claim 1 characterized by the pick up lift assembly including a rope attached to the lift arm which runs around a shaft for driving the baler pick-up that forms a capstan type drive.
6. The improved hay baler of claim 1 characterized by the pick-up including at least one gage wheel.
7. The improved hay baler of claim 2 characterized by said lost motion mechanism including a compression spring which tend to raise the pick-up.

* * * * *
